Term of patent 14 years

(Cl. D26—14)

Fig. 1.

Fig. 2.

Fig. 3.

Fig. 4.

FIG. 1 is a perspective view of a portable tape recorder, showing the top and front of my new design with the hinged cover thereof in closed position;

FIG. 2 is a perspective view of same illustrating the top and left side walls;

FIG. 3 is a perspective view of same illustrating the top and right side walls;

FIG. 4 is a perspective view of same illustrating the rear side and bottom walls; and

FIG. 5 is a perspective view looking down upon the escutcheon face of the recorder with the cover in open position and also illustrates the front and right sides of same.

The fragmentary showing in dots of a grill in FIGS. 1 and 5 is continuous, except for a dial, throughout the area enclosed by the border frame of the front panel.

I claim:

The ornamental design for a portable tape recorder, as shown and described.
